THREAD CUTTING TOOL

Charles Zimmermann, Cincinnati, Ohio

Application July 3, 1941, Serial No. 401,032

9 Claims. (Cl. 10—101)

This invention relates to a tool of simple construction adapted to be used for cutting threads in rods, pipes and the like, and more particularly to a tool provided with a plurality of cutting bits for engaging the member to be threaded and at longitudinally spaced points relatively thereto.

More particularly, it is an object of the invention to provide a thread cutter of simple construction adapted to be readily attached to a conventional lathe and which is adapted to be supported thereby for engaging a member to be threaded which is rotatably mounted in the lathe.

A further aim of the invention is to provide a thread cutting tool having means whereby the cutting depth of the various cutting bits can be varied relatively to one another thus providing means whereby each of the cutting bits will partially form the thread to thus reduce the amount of pressure on each of the bits to permit the cutting operation to be performed at a much greater speed than with conventional thread cutters having but a single cutting bit.

Still another object of the invention is to provide means for adjustably positioning the cutting bits relatively to one another so that the spaces between the cutting bits can be varied for forming a thread of any desired pitch.

Still a further aim of the invention is to provide means whereby the individual cutting bits can be readily released and moved to retracted positions so that while certain of the cutting bits are in projected, operative positions functioning for cutting the thread, other of the cutting bits can be in retracted positions and out of engagement with the member being threaded.

Other objects and advantages of the invention will hereinafter become more fully apparent from the following description of the drawings, which illustrate a preferred embodiment of the thread cutting tool, and wherein—

Figure 1 is a top plan view of the tool.

Figure 2 is an end view in elevation of the same, showing the tool detachably clamped to a portion of a lathe.

Figure 3 is a cross sectional view taken substantially along the plane of the line 3—3 of Figure 1.

Figure 4 is a longitudinal vertical sectional view taken substantially along the plane of the line 4—4 of Figure 2.

Figure 5 is an enlarged horizontal sectional view of a portion of the tool, taken substantially along a plane indicated by the line 5—5 of Figure 3.

Figure 6 is a vertical sectional view taken sub-

stantially along the plane of the line 6—6 of Figure 5.

Figure 7 is a vertical sectional view taken substantially along the plane of the line 7—7 of Figure 1.

Figure 8 is a horizontal sectional view of a portion of the tool taken substantially along a plane indicated by the line 8—8 of Figure 3, and

Figure 9 is a plan view, on a reduced scale, of a guide for setting the individual cutting bits, relatively to one another.

Referring more particularly to the drawings, wherein like reference characters designate like or corresponding parts throughout the different views, 10 designates generally a portion of a lathe carriage which is provided with an upwardly opening inverted T-shaped slot 11, as best seen in Figures 2 and 3. 12 designates a portion of the headstock spindle of the lathe, not shown, to which is connected in any suitable manner, a piece of work 13, which is illustrated as a rod and which is intended to be threaded by the thread cutting tool, designated generally 14. The parts 10 and 12 form parts of a conventional lathe and form no part of the present invention but are shown and described merely to better illustrate the application and use of the thread cutter 14 which is not a part of the lathe but which is adapted to be detachably connected thereto and to operate in conjunction therewith. The thread cutting tool 14 includes an elongated base 15 which is mounted on the carriage 10 longitudinally of its slot 11. The base 15 is provided with removable upstanding end walls 16 having upwardly and rearwardly enlarged rear portions 17.

A plate 18 is detachably supported at its ends on the upper edges of the forward portions of the end walls 16. Bolts 19 extend through registering openings 20 in the end walls 16 and the ends 40 of the plate 18, and said bolts 19 extend into threaded openings 21 in the ends of the base 15 to provide means whereby the lower, threaded ends of the bolts 19 are threadedly connected to the base 15 for detachably securing the end walls 16 to the base and the plate 18 to the upper edges of the end walls 16. A bolt 22 extends through the parts 15, 16 and 18, at each end of the tool 14. The bolts 22 are provided with lower threaded ends which extend into the slot 11 and which engage threaded openings 23 in the ends of a bar 24 which is disposed in the enlarged, bottom portion of the slot 11 for clamping the thread cutting tool 14 to the carriage 10.

As seen in Figure 3, the plate 18 combines with the top of the base 15 to form an elongated hori-

zontally disposed slot 25 which opens outwardly of the front side 26 of the tool 14 and which also opens outwardly of and terminates near the rear side 27 of the base 15. The plate 18 is provided with a longitudinally extending, elongated opening 28 near the front side 26 and which opens into the slot 25. A plurality of guides, designated generally 29 are slidably mounted in the opening 28, and in the embodiment of the invention as disclosed, three guides 29 are provided. The guides 29, as best seen in Figures 3 and 7, each includes an enlarged lower portion 30 which is disposed in the slot 25 and which is provided with a downwardly opening slot 31 which extends therethrough, transversely of the tool 14. The guide 29, above its enlarged portion 30, is provided with a restricted portion 32 which is disposed in slidable engagement with the opening 28 and which combines with the portion 30 to form a surrounding shoulder 33 which engages the underside of the plate 18. Guide 29, above its portion 32, is provided with a restricted upwardly extending externally threaded post 34 having a threaded longitudinally extending bore 35 for receiving a screw 36, the head of which is disposed above the upper end of the post 34. A washer 37 is mounted on the post 34 and rests against the upper side of the plate 18, and a nut 38 engages the threaded portion of the post 34, above the washer 37. The nut 38 may be of any conventional type and is illustrated as being of a type adapted to be turned by means of a spanner wrench, not shown.

An elongated cutting bit 39 extends through the slot 31 of each guide 29. The number of cutting bits 39 corresponds to the number of guides 29, and said cutting bits 39 are disposed in the slot 25 and transversely of the tool 14, and are provided with sharpened cutting ends 40 which project outwardly from the front side 26 of the tool 14.

Referring to Figures 3, 5 and 6, the cutting bits 39 are provided, near their opposite ends, with oppositely disposed outwardly opening recesses 41. Each of the bits 39 is connected to a block 42. Each block 42 is provided with a forwardly opening recess 43 for receiving the recessed, rear end of a bit 39. The block 42 is provided with set screws 44, disposed on opposite sides of the recess 43 and which extend inwardly thereof for engaging the recesses 41 for detachably connecting the block 42 to the bit 39. The block 42 is provided at its rear end with an upwardly opening T-shaped slot 45. A feed screw 46 is connected to each of the blocks 42. Each feed screw 46 is provided with an outer headed end 47 and an inner end which is provided with a collar 48, a restricted stem portion 49 which projects outwardly from the collar 48, and a head 50 on the outer end of the stem 49. Stem 49 and head 50 turnably engage the T-shaped slot 45 for swivelly connecting the feed screw 46 to the block 42. Blocks 42 rest on top of the base 15 and are disposed in or partly in the slot 25, as seen in Figure 3.

Each of the feed screws 46 is provided with a collar or nut 51 which is turnably mounted on the threaded shank portion thereof, as best seen in Figure 4. The collars or nuts 51 are provided with diametrically opposed outwardly projecting pins or studs 52. The portions 17 of the end walls 16 are provided, adjacent their rear ends, with alined openings 53 for receiving the ends of a rod 54 which extends therebetween and which is secured at its ends to the portions 17 by set screws 55. Three levers 56 are pivotally

mounted near their lower ends on the rod 54. The levers 56 are provided with openings 57 through which the rod 54 loosely extends so that the levers 56 are not only pivotally but slidably mounted on the rod 54. Levers 56 are provided with handle portions 58 at their upper ends, and at their lower ends, the levers 56 are bifurcated as seen at 59. As seen in Figures 2 and 3, the furcations 60 of each of the bifurcated portions 59 are each provided with a corresponding downwardly opening slot 61. Each of the bifurcated portions 59 is adapted to engage loosely over a nut or collar 51 and the pair of pins 52 thereof are adapted to loosely engage in the slots 61 of the furcations 60 thereof for pivotally and slidably connecting each lever 56 to a feed screw 46. The portions 17, adjacent their forward ends, are provided with alined openings 62 for receiving the round ends of a rod or shaft 63. The portion of the shaft 63 which is disposed between the end wall portions 17 is square in cross section, as seen in Figure 3, and the rounded ends of the shaft 63 are prevented from rotating in the openings 62 by means of set screws 64, which provide means for securing the shaft 63 so that its sides are at any desired angles relatively to the horizontal and perpendicular and, as seen in Figure 3, one side of the shaft 63 faces upwardly and slightly rearwardly. A latch arm 65 is pivotally mounted on a screw 66, intermediate of its ends, on each lever 56. Latch arms 65 are pivotally connected to the levers 56 between the rod 54 and their upper, handle ends 58. Each latch member 65 is provided with a handle portion 67 at its upper end. The lower ends of the latch members 65 are each provided with a flat portion 68, which is disposed substantially at a right angle to the longitudinal axis of the latch member and an extension 69 which forms a continuation of the forward longitudinal edge of the latch member, and which extends beyond the flat portion 68. When the levers 56 are disposed so that their handle ends 58 are inclined only slightly forward, the flat end portions 68 can be disposed to engage flush against the upper side of the rod 63 and the extensions 69 will engage flush against the forward side of the rod 63 to prevent the levers 56 from being swung forwardly of the thread cutting tool 14, at their upper ends.

An anchor member 70 is mounted in each lever 56, near its upper, handle end 58, and each of said anchor members 70 is provided with a forwardly projecting eyelet 71 to which is connected one end of a contractile coil spring 72, the opposite end of which is clamped between the head of the screw 36 and the upper end of the post 34, of the guide 29 which is disposed in transverse alignment with said lever 56. It will thus be seen that the springs 72 tend to urge the upper ends of the levers 56 forwardly and the latch members 65 and the rod 63 are provided to retain the levers 56 in the full line positions of Figures 2 and 3, against the action of the springs 72.

The lathe carriage 10 is adapted to be moved parallel to the longitudinal axis of the rod 13 for moving the cutting tool 14 in a similar direction. The work 13 is adapted to be revolved by the headstock stem 12 and the rotation thereof is synchronized with the movement of the carriage 10, in a conventional manner, so that the thread cutting tool 14 will be moved a predetermined distance relatively to the work 13 at each revolution of the work. The bits 39 are set so that their cutting ends 40 will cut to the desired depth by positioning each of the levers 56 and each of the

latch members 65, carried thereby, in the position, as indicated in full lines in Figure 2 so that the cutting bits 39 will be in projected positions. The cutting bits 39 can then be adjusted forwardly or rearwardly by turning their follower screws 46 to position them to cut to the desired depth, and the bits 39 are preferably positioned so that the leading bit 39 will partially form the thread, the intermediate bit 39 will further complete the cut, and the bit 39 at the opposite end 10 of the tool 14 will complete the finished cut to form the thread. By loosening the nuts 38 the guides 29 can be slid longitudinally of the tool 14 and the feed screws 46 connected to the bits 39 of the guides 29 and the levers 56, connected to the feed screws 46, will, together with the feed screws, be moved in conjunction with the guides 29 and the bits 39 to thus provide means for adjustably positioning the bits relatively to one another so that they can cooperate to cut threads 20 of any desired pitch. As seen in Figure 1, the leading cutting bit 39 has completed its cutting operation on the rod 13 and has been released by a downward pressure on the latch handle 67 which released the latch of the lever 56 associated with the bit, so that its spring 72 could retract the leading bit to prevent it from striking the spindle 12. As a result, this leading bit 39 is disposed in an inoperative position while the other two cutting bits are still functioning, and it will be readily apparent that this could readily be accomplished without interruption of the operation of the tool 14. In Figure 9 a setting gage, designated generally A, is shown which can be employed for correctly spacing the bits 39 for cutting a thread of a certain pitch by inserting the cutting ends 40 into the notches a thereof, which are shaped to fit the cutting ends 40. The gage A can thus be employed not only for spacing the bits 39 relatively to one another but also for adjusting the cutting depths of the different bits by varying the positions of the ends 40 relatively to the notches a. It will be obvious that a plurality of guides or setting members A could be provided having differently spaced notches a for setting the bits 39 for cutting threads of different pitches.

It will be apparent that to release the tool 14 to enable it to be returned to a position for making another cut, it is only necessary to press downwardly on the latch handles 67 to release the latches 65 so that the springs 72 can act on the levers 56 for retracting the cutting bits 39, inwardly of the slot 25. Consequently, if another piece of work 13, of the same diameter, is to be chased with a thread of the same depth and pitch, it will only be necessary to return the levers 56 to the full line position of Figure 2 to again project the bits 39 to their correct cutting positions, after the carriage 10 and tool 14 have been returned to a position to begin another thread cutting operation.

The thread cutting tool can be made for any size engine lathe and the tool can be provided with either three or four cutting bits.

Various modifications and changes are contemplated and may obviously be resorted to, provided they fall within the spirit and scope of the invention as hereinafter defined by the appended claims, as only a preferred embodiment of the invention has been disclosed.

I claim as my invention:

1. A thread cutting tool comprising a base adapted to be detachably clamped to a portion of a lathe, said base being provided with upright

5 end walls, a plate detachably fastened to said end walls and disposed above and spaced from the forward portion of said base, said plate being provided with a longitudinal slot, a plurality of guides slidably mounted in said slot, a plurality of cutting bits slidably engaging said guides and disposed to move transversely of the base, feed screws swivelly connected to the rear ends of said bits and projecting rearwardly from the thread cutting tool, a collar threadedly engaging each of said feed screws, each of said collars being provided with diametrically opposed outwardly projecting studs, a plurality of levers slidably and pivotally mounted on the thread cutting tool, said levers having yoke shaped lower ends for engaging over said collars, said yoke shaped ends being slotted to engage said studs, spring means for urging the upper ends of said levers forwardly of the tool for retracting the feed screws and cutting bits, and latch means carried by said levers for holding the cutting bits and feed screws in projected positions.

2. A thread cutting tool as in claim 1, said guides being movable relatively to the plate for moving the cutting bits, feed screws and levers longitudinally of the base for adjustably spacing the cutting bits relatively to one another.

3. A thread cutting tool as in claim 1, said guides being movable relatively to the plate for moving the cutting bits, feed screws and levers longitudinally of the base for adjustably spacing the cutting bits relatively to one another, and said guides being provided with clamping means for engaging the plate for retaining the cutting bits in adjusted positions relatively to one another.

4. A thread cutting tool as in claim 1, comprising a rod detachably mounted in the rear ends of said end walls and on which said levers are pivotally and slidably mounted, a second rod detachably mounted at its ends in said end walls and forwardly of said first mentioned rod, said second rod being square in cross section, and said latch means including pivotally mounted lever arms carried by said levers and having lower end portions for detachably engaging said second rod for preventing the upper ends of said levers from being swung forwardly by the action of said spring means to retain the cutting bits in projected positions.

5. A thread cutting tool comprising a plurality of cutting bits, the longitudinal axis of said tool being disposed parallel to the longitudinal axis of the member to be threaded thereby, said cutting bits being spaced from one another longitudinally of the tool and being disposed transversely thereof, guide means for slidably mounting said bits, said guide means being movable longitudinally of the tool for adjustably spacing the bits from one another, pivotally mounted levers connected to said bits for advancing and retracting the bits, and latch means associated with said levers for holding the bits in projected positions.

6. A thread cutting tool as in claim 5, comprising spring means for normally urging the bits to retracted positions.

7. A thread cutting tool as in claim 5, comprising means for adjustably connecting said levers to the bits for varying the cutting depth of the bits, when in their projected positions.

8. A thread cutting tool comprising a tool frame provided with a plurality of cutting bits, said cutting bits being spaced from one another in a direction parallel to the longitudinal axis of a member to be threaded thereby, means for ad-

justably spacing the cutting bits from one another, said cutting bits being slidably mounted relatively to the tool frame to slide in directions parallel to one another, levers connected to said cutting bits for projecting and retracting the cutting bits, and latch means carried by said levers for holding the cutting bits in projected positions.

9. A thread cutting tool as in claim 8, comprising means for adjustably connecting said cutting bits and levers for adjusting the cutting depth of the bits, when in projected positions, independently of one another.

CHARLES ZIMMERMANN.
